CLAIM

An ornamental design for a dispensing container, as shown and described.

DESCRIPTION

FIG. 1 is a perspective view of a dispensing container showing my new design;

FIG. 2 is a top plan view thereof, the undisclosed opposite side being identical;

FIG. 3 is a side elevational view thereof, the undisclosed opposite side being a mirror image; and,

FIG. 4 is a left end view thereof, the undisclosed opposite side being a mirror image.

FIG. 1

FIG. 2

FIG. 3

FIG. 4
